DRAFTSMAN.

Des. 5826

CHARLES LIPPINCOTT, OF PHILADELPHIA, PENNSYLVANIA, ASSIGNEE TO
CHARLES LIPPINCOTT & CO., OF SAME PLACE.

DESIGN FOR SODA-WATER APPARATUS.

Specification forming part of Design No. 5,826, dated April 30, 1872.

Specification describing a Design for Soda-Water Apparatus, invented by CHARLES LIPPINCOTT, of Philadelphia, Pennsylvania.

Design for Soda-Water Apparatus.

The figure in the accompanying drawing is a perspective view of a soda-water apparatus made in accordance with my design.

The top A of the apparatus is made in the form of the roof of a Mansard cottage, it having curved and sloping sides *a a* approaching each other at the top, and surmounted, in the present instance, by a cap piece, *b*, partly curved and partly straight, and projecting beyond the said curved sides *a a* so as to form an ornamental molding or cornice, *d*, above the latter. The curved and sloping sides *a a*, however, may be brought together at the top without the cap piece, so as to form a sharp angle, or they may be rounded one into the other. The body B of the apparatus is rect-

angular, and is formed with the usual paneled sides, ornamented with tablets, and provided with the usual draught-tubes and syrup-faucets. This portion of the apparatus, however, forms no part of my design.

Irrespective of the finish at the extreme top of the apparatus, I claim—

1. The design for the top of a soda-water apparatus, consisting of curved and sloping sides *a a*.

2. The design for the top of a soda-water apparatus in which curved and sloping sides *a a* are combined with a cap piece, *b*.

In testimony whereof I have signed my name to this specification in the presence of two subscribing witnesses.

CHAS. LIPPINCOTT.
